UNITED STATES PATENT OFFICE.

LEONTINE DANDEVILLE DE LAITTE, OF SAN FRANCISCO, CALIFORNIA.

NAIL FILING AND POLISHING MACHINE.

Application filed June 9, 1926. Serial No. 114,596.

This invention relates to a nail filing and polishing machine, this application being filed as a continuation in part of my application entitled "Nail filing and polishing machine", filed June 9, 1926, S. N. 114,597.

The object of the present invention is to provide a machine which carries a filing or buffing wheel and which is so small and so shaped that it may be readily clasped in one hand while filing or polishing the finger nails on the other hand; to provide a train of step-up gears whereby a high speed rotary movement may be transmitted to the file or buffing wheel, and further to provide means whereby gripping or pressure application of the hand may be transmitted to rotate the gears and the buffer driven thereby.

One form which my invention may assume is exemplified in the following description and illustrated in the accompanying drawings, in which—

Fig. 1 is a side elevation in section of the machine.

Fig. 2 is a plan view in section taken on line 2—2.

Fig. 3 is a plan view of the machine.

Referring to the drawings in detail and particularly to Figs. 1, 2 and 3, A indicates in general a rectangular shaped frame consisting of parallel side members 2—2 and end sections 3 and 4. Journalled crosswise of the frame are a plurality of shafts indicated at 5, 6, 7 and 8. Secured on the shaft 5 is a spur driving gear 9. Secured on the shaft 6 is a pair of intermediate spur gears 10 and 11. Similarly secured on shaft 7 is a pair of intermediate spur gears 12 and 13, and secured on shaft 8 are a spur gear 14 and a bevel gear 15.

Mounted on one side of the driving gear 9 is a roller clutch generally indicated at B. This clutch consists of an inner section 16 which is secured to shaft 5 and an outer section 17 which is provided with an operating lever or arm 18. The inner face of the member 17 has a series of inclined recesses formed therein as shown at 19, and rollers 20 are interposed between the inclined faces and the member 16, so that when a rotary movement is transmitted to the member 17 in one direction, the rollers will grip and rotate the member 16, while movement of the arm 18 and member 17 in the opposite direction will permit the member 17 to re-

55 turn without imparting rotary movement.

Pivottally mounted at one end of the rectangular frame as at 21 is an operating lever 22. Forming a connection between the lever and the arm 18 is a link 23, and connected with lever 22, so as to normally hold it in the dotted line position shown at 22^a, is a spring 24.

Journalled in the end 4 of the rectangular frame and disposed at right angles to the shafts 5, 6, 7 and 8, is a driven shaft 25. Secured on the inner end of the shaft is a bevel gear 26 which remains in constant mesh with the bevel gear 15, and adapted to be secured on the outer end of the shaft is a detachable buffing or filing wheel generally indicated at 27.

The machine so far described has been particularly designed for the purpose of polishing and filing finger nails, and it is designed to be manually operated by pressure on the operating lever 22. It is accordingly necessary that the frame A which carries the driving mechanism be as small as possible so that it may be placed conveniently in the hand of an operator when in actual use. It is also essential that the frame be enclosed in a casing generally indicated at C, and that this be shaped so as to conform to the contour of the hand as much as possible.

If these conditions are complied with, it is obvious that a person desiring to file and polish his or her finger nails may place the machine in one hand and may rotate the filing or buffing wheel at a high speed by merely depressing the operating lever 22 by gripping action. Depression of the operating lever about the pivotal point 21 transmits an oscillating movement to the arm 18 and the member 17 of the roller clutch. This movement is transmitted through the rollers to rotate the inner clutch member 16, and as this is secured to the shaft 5 rotation will be transmitted thereto. This rotation is in turn transmitted to the driving gear 9, as this is also secured on the shaft, and this rotary movement is transmitted through the gears 10, 11, 12, 13 and 14, to the bevel gears 15 and 16, and shaft 25, together with the buffing or filing member 27 carried thereby, is thus rotated at a high speed when the operating lever is depressed. It is thus possible to quickly file or polish the nails.

The buffing member 27 is detachable, a

disk having filing surfaces formed thereon being applied when it is desired to file the nails and a buffing wheel being applied when it is desired to polish the nails. The spring 5 24 serves the function of raising or returning the operating lever when it has been depressed its whole limit. This movement is not transmitted to rotate the shafts and gears as the roller clutch turns freely when 10 the operating lever is raised. The intermittent rotary motion is accordingly transmitted through the roller clutch, the gears, and the buffing member when in actual operation. The speed of the buffing member may be increased or decreased as desired by varying 15 the gear ratios, and practically any result desired may thus be obtained.

Another feature of the invention is the provision of a fly-wheel such as generally 20 indicated at 30. This fly-wheel is secured on the shaft 7 and accordingly rotates therewith. The fly-wheel is made as heavy as possible, as this is exceedingly important; that is, the power transmitted to rotate the 25 buffing or grinding wheel 27 is intermittently applied through the lever 22. This power is stored up to a certain extent in the fly-wheel and the momentum of the fly-wheel will accordingly rotate the buffer 27 at a 30 fairly continuous speed.

The fly-wheel may, of course, be mounted on any one of the shafts 5, 6 or 7, but preferably on the shafts 7 or 8, as the rotating 35 speed of these shafts is the greatest. Practical experience has proven that the use of a fly-wheel or weighted rotating member is exceedingly desirable as the rotary movement of the buffer is otherwise too variable.

In actual practice the power from the 40 lever 22 is transmitted through the clutch B and the gears 9, 10, 11 and 12, to rotate shaft 5 and the fly-wheel carried thereby. The energy stored up in the fly-wheel when it is set into rotation is in turn transmitted 45 through the gears 13 and 14 to the bevel gears 15 and 26, and from these gears the power is transmitted through shaft 25 to the buffer. It is for this reason that a fairly continuous speed is obtained.

50 While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

60 To prevent accidental pinching of the flesh between the operating lever 22 and the casing, side extensions such as indicated at 22^b are provided, these extensions being so arranged as to telescope in the casing C 65 when the lever is operated. It should also

be noted that shaft 7 may be extended through one side of the casing so that a grinding wheel may be attached thereto as indicated at 27^a.

Having thus described my invention, what 70 I claim and desire to secure by Letters Patent is—

1. A device of the character described comprising a casing adapted to be placed in the hand of an operator and gripped thereby, 75 a shaft journalled in the casing and projecting through one end thereof, a buffing member on the shaft, a step-up gear train journalled in the casing and adapted to drive the shaft, an operating lever pivotally mounted on the casing, spring means normally holding the lever in one position, said lever adapted to be gripped and depressed by hand pressure, and means for transmitting movement of said operating lever when depressed by hand pressure to drive the gear train and the shaft. 85

2. A device of the character described comprising a casing, a shaft journalled therein and projecting through one end thereof, 90 a buffing member on said shaft, a step-up gear train mounted in the casing and adapted to drive said shaft and buffing member, a roller clutch adapted to transmit rotary movement to the gear train in one direction, 95 and manually operated means for transmitting an oscillating movement to said roller clutch.

3. A device of the character described comprising a casing, a shaft journalled therein and projecting through one end thereof, 100 a buffing member on said shaft, a step-up gear train mounted in the casing and adapted to drive said shaft and buffing member, a roller clutch adapted to transmit rotary 105 movement to the gear train in one direction, an operating lever pivotally mounted on one end of the casing, said operating lever adapted to be manually depressed in one direction, means for transmitting said movement to rotate the roller clutch in one direction, and spring actuated means for rotating the roller clutch in an opposite direction and for reversing the movement of the 110 operating lever. 115

4. A device of the character described comprising a casing, a shaft journalled in the casing and projecting therethrough, a buffing member on said shaft, a ratchet clutch, means for manually transmitting an oscillating movement to said clutch, a second shaft within the casing, a fly-wheel thereon, a gear train interposed between the fly-wheel and the clutch and adapted to transmit the oscillating movement of the 125 clutch to rotate the fly-wheel, and means for transmitting the rotary movement of the fly-wheel to rotate the first-named shaft and the buffer carried thereby. 130

5. A device of the character described 130

comprising a casing adapted to be held in the hand of an operator, a shaft journalled in the casing and projecting therethrough, a buffing member on the outer end of said shaft, an oscillatory lever connected with the casing and lying substantially parallel thereto, a driving mechanism in the casing oper-

atively connected with said shaft, and a connecting mechanism connecting said lever with said driving mechanism whereby oscillation of said lever will drive said driving mechanism to revolve the buffing member in one direction. ¹⁰
